AILERON DEVICE

Edward F. Zaparka, Baltimore, Md., assignor to
 Zap Development Corporation, Baltimore, Md.,
 a corporation of Delaware

Application June 7, 1933, Serial No. 674,729
 Renewed January 13, 1937

17 Claims. (Cl. 244—90)

My invention relates to ailerons, and more particularly to ailerons which are balanced so that it requires gradually increasing control stick forces to move them from the neutral position.

5 Though I am not to be limited to any particular location of the ailerons, the ailerons I have shown are of the type illustrated and described in my application Serial No. 653,918, filed January 27, 1933.

10 The present application deals with the construction of the aileron per se, and the location of the aileron as specified in Serial No. 653,918 is not restrictive in considering claims in this application, except as the language imposes such

15 limitations.

Heretofore when a pair of ailerons moved in opposite directions from the neutral position, there was a "soupy" action at the control stick for the first few degrees of movement of the pair 20 of Zap ailerons from the neutral position. This soupy action was followed by a very sharp increase in the stick forces necessary to move the pair of Zap ailerons when the change from the vertical angle became great.

25 It is one of the objects of this invention to provide ailerons such that the forces necessary to move the pair of Zap ailerons through increasing plus and minus angles of attack is considerably less than for a pair of normal Zap ailerons.

30 It is a further object of this invention to provide ailerons in which the center of pressure shift at varying angles of attack creates favorable hinge moments.

35 A still further object of my invention is to provide aileron constructions which are so pivoted that the pivot shifts with the angular movement of the aileron so that the shift in center of pressure is compensated largely by varying the moment arm between the center of pressure and 40 the point of pivoting.

Still another object of my invention is to provide ailerons so constructed that the tendency for the center of pressure to shift on any one designed area of an aileron in one direction is compensated for by shift of center of pressure in the opposite direction on another designed area, whereby there is a tendency for these opposite shifts in center of pressure on the different designed areas to at least in part neutralize each other.

In the drawings:

Figure 1 is a top plan view of an airplane equipped with one form of my aileron;

55 Fig. 2 is a detail view in side elevation of a

wing equipped with the form of aileron shown in Figure 1;

Fig. 3 is a graph showing the control stick forces plotted with respect to the angle of attack of a combined pair of ailerons;

Fig. 4 is a view in side elevation of an airplane wing showing another form of my aileron;

Fig. 5 is a detail view partly in section showing the form of aileron illustrated in Figure 4, the different positions of the aileron being indicated by dotted lines;

Fig. 6 is a detail view in side elevation and partly in section showing another form of aileron, the different positions being indicated in dotted lines;

Fig. 7 is a detail view in side elevation and partly in section showing another form of aileron, the different positions being indicated in dotted lines;

Fig. 8 is a detail view in side elevation and partly in section showing another form of aileron, the different positions being indicated in dotted lines;

Fig. 9 is a detail view in side elevation and partly in section showing another form of aileron, the different positions being indicated in dotted lines;

Fig. 10 is a side elevation of another modification of my aileron, the different positions being indicated in dotted lines;

Fig. 11 is a rear elevational view of a wing showing a different form of my aileron in position above the wing;

Fig. 12 is a detail view in side elevation of the aileron illustrated in Figure 11.

Referring to the drawings, in Figures 1 and 2 I have shown a form of my aileron having a front slot construction. In Figure 1 I have shown an aileron having a fuselage 1, a motor 2, propeller 3 and wings 4. Above the wings 4 and

near the trailing edge thereof, as shown in the drawings, I have mounted ailerons 5. The ailerons 5 are mounted on horns 6; the ailerons being pivoted at 7 on the horns 6. The ailerons have attached to their upper surface horns 8 to which 40 are pivoted at 9 the aileron control rods 10. 45 Empennage surfaces are indicated at 4'.

The aileron control rods 10 are pivoted at 11, as diagrammatically illustrated in Figure 1, to a control member 12, which is pivoted at 13. The 50 control member 12 is provided with two arms 14 and 15, indicated in dotted lines. The arms 14 are connected by a cable 16 and the arms 15 are connected by a cable 17. The cable 17 passes over pulleys 18 and is attached to a control stick 55.

19. The aileron control mechanism is of the well known type and the details of construction are not given herein.

Spaced from the upper front edge of the aileron 5 is an element 20 which has a curved front surface and is so shaped at its rear as to provide a substantially parallel slot 21 which slopes backwardly and upwardly above the upper leading edge of the aileron 5. The element 20 is supported in its spaced relationship to the upper leading edge of the aileron 5 by means of support elements 22, only one of which is shown.

Referring to Fig. 3, I have shown a graph in which the control stick forces in pounds necessary to accomplish a certain movement of a pair of Zap ailerons in minus or plus directions from the neutral position are indicated. The dotted line indicates the action of a pair of Zap ailerons placed as shown in Fig. 2, but without the slotted front construction just described. The unbroken line on the graph indicates the stick forces plotted with respect to a pair of Zap ailerons with leading edge fixed slots. Both lines approximate actual performance.

25. From an inspection of the dotted line in Fig. 3, it will be seen that for the first few degrees of movement of the pair of ailerons from their neutral position the feel on the control stick is what is known to pilots as "soupy". The forces necessary to move the pair of ailerons then become sharply greater, and at about ten degrees in the particular graph shown, the force to move an ordinary pair of Zap ailerons not provided with the leading edge fixed slot is about the same as that to move a pair of Zap ailerons provided with the leading edge fixed slot. From ten degrees on the forces required to move the pair of ailerons to increase minus and plus angles of attack are very much greater than is the case with the pair of Zap ailerons provided with the leading edge slot.

With the form of aileron just described, I have found that in certain instances lift increase on the positive aileron is between 18 and 20 per cent, 45 and this produces a rolling moment on the whole airplane which gives an increase of about 10 per cent in total rolling moment over the conventional pair of Zap ailerons. Furthermore, it is possible to balance the ailerons considerably 50 farther aft which will permit exceedingly light stick forces and, therefore, lighter mechanism. Conversely, Zap ailerons, not equipped with the flap, when given a pivot point such that there is a favorable location for balance, so that negative 55 hinge moments which might cause flutter are largely eliminated, have, in certain instances, high stick forces. Because of high stick forces, the rapid control of the airplane is in some instances somewhat difficult.

60. With the conventional Zap aileron it was found that with the point of pivot about 22 to 25 per cent back from the leading edge, a flutter sometimes occurred at low angles because of negative hinge moments. When the pivot point was moved 65 up to about 18 per cent, the flutter was eliminated but stick forces tended to become large because of the forward location of the pivot.

When using the type of aileron with the fixed leading edge slot construction just described, 70 there are numerous advantages. Some of the advantages are that;

(1) The pivot point of the aileron can be moved to the rear, preventing fluttering;

(2) Due to relatively great rearward movement of the pivot favorable hinge moments are

obtained, i. e. stick forces are such that the pilot can control the plane easily;

(3) Additionally an increased rolling moment is obtained due to the increased lift of the positive aileron, which is in some instances in the 5 nature of 20 per cent increase in lift of positive aileron, and, therefore, a 10 per cent increase in total rolling moment.

In Figs. 4 and 5 I have shown the aileron 5 provided with a supplemental airfoil 23, pivoted at 10 24 to the trailing edge of the aileron 5. The supplemental airfoil 23 is provided with a horn 25 to which is pivoted at 26 a link 27 whose other end is pivoted at 28 to the supporting horn 6 for the aileron 5.

15 In Fig. 5 the interior construction of the aileron 5 is shown, which is similar to the forms shown in Figs. 1 to 8, namely a construction in which there is a front hollow bracing tube 29 having supports 31 pivoted at 7 on the upper tip of the 20 horn 6. There are provided slots 33 to permit the horns 6 to pass into the interior of the aileron 5. The position of the aileron 5 with respect to the flap or supplemental airfoil 23 in varying 25 positions is shown in dotted lines in Fig. 5.

Here the supplemental airfoil or flap 23 and the linkage indicated causes a phenomenon similar to that in the form of aileron shown in Fig. 2, namely a reduction in the hinge moment of the 30 pair at high plus and minus angles of attack. Moreover, the flap increases the rolling moment of the pair due to the down aileron.

In the form of aileron shown in Fig. 6, the aileron 5 is provided with a split flap type of construction in which there is a flap 34 pivoted at 35 35 to the lower rear surface of the aileron 5. It is to be noted that the aileron 5 is of the single cambered type with a cambered upper surface. The flap 34 in its up position forms a continuation of the lower surface of the aileron and has 40 its trailing edge substantially adjacent the trailing edge of the aileron. Projecting into the interior of the aileron 5 is a horn 36 fastened to the upper front surface of the flap 34. Pivoted to the horn at 37 is a link 38 whose other end is provided with a slot construction 39 which fits over a pivot 41 provided on the support arm 6. There is provided a spring 42 attached at 43 to some 45 suitable portion of the interior of the aileron 5 at one end, and at the other end attached to 50 the horn 36 on the flap 34.

The spring 42 is a tension spring and tends to hold the flap 34 in the position indicated in Fig. 6. When the aileron moves in the up position (with its trailing edge raised, as indicated in 55 dotted lines) the pivot 41 merely slides in the slot 39 formed in the link 38 and the spring 42 holds the flap 34 in the shut or up position.

Upon down movement of the aileron 5, however, the pivot 41 strikes against the end of the slot 39 60 formed in the link 38 and through the linkages indicated forces the flap 34 into the open position, as indicated in dotted lines in Fig. 6. This form of construction is peculiarly adapted to a single cambered aileron and tends to decrease the hinge 65 moments of the pair at high plus and minus angles of attack and to increase the rolling moment of the pair due to the down aileron.

In Fig. 7 I have shown a construction somewhat 70 similar to that shown in Fig. 6. The aileron 5, however, is of the double cambered type and there is provided a flap 44 pivoted at 45 on the upper surface of the aileron 5. The trailing edge of the flap lies substantially adjacent and just above the 75 trailing edge of the aileron. The lower front edge

of the flap 44 is provided with a horn 46 to which is pivoted at 47 the link 38 which is identical in construction with the link 38 of the construction shown in Fig. 6. A spring 48 is attached to the flap horn 46, and also attached at 49 to the interior of the aileron 5.

In the up position of the aileron shown in Fig. 7 there is no movement of the flap since the slotted portion 39 of the link 38 slides over the pivot 41. 10 and the spring 48 holds the flap shut. In the down movement of the aileron, when the trailing edge of the aileron is lowered, however, the pivot 41 strikes the end of the slot 39 and the flap 44 is opened against the tension of the spring 48. The 15 hinge moments at high plus and minus angles of attack are reduced so that the stick forces approximate those indicated in the unbroken line of the graph, Fig. 3.

In Fig. 8 I have shown the aileron 5 as single cambered with relatively flat lower surface and a cambered upper surface. The aileron 5 is provided with a flap 51 whose trailing edge lies adjacent and just below the trailing edge of the aileron 5. The flap 51 is provided with an attachment member 52, which is pivoted on a pivot member 53 which is also pivoted to the link 38. The pivot 53 is adapted to pass through and slide in a slot 54 formed in a bracing rib 55 of the aileron. Pivoted at 56 to the upper side of the flap 51 is a link 57 30 which is also pivoted at its other end 58 to the interior of the aileron construction.

The link 38 is adapted to pass through an aperture 59 formed in the lower surface of the aileron 5. In up positions of the aileron, as shown in Fig. 8, there is a spring 59 attached at 61 to the interior of the aileron 5 and attached at its other end to the support 52 which prevents the flap 51 from opening.

However, when the aileron is lowered (its trailing edge lowered) the pin 41 engages the end of the slot 39 in the link 38 and forces the flap to a down position with respect to the aileron, as indicated in dotted lines. The lengths of linkage and points of pivoting are such as to cause the trailing 45 edge of the flap to lie substantially in the locus of perpendiculars drawn to the datum lines of the aileron sections which pass through the trailing edge of the aileron. This type of flap is called a "Zap" and I have found it of peculiar utility in 50 connection with the type of aileron shown in Figure 8.

With the form of ailerons depicted in Fig. 8 there is an increased rolling moment and a reduction in hinge moments for the pair at high plus 55 and minus angles of attack.

In Figure 9 I have shown an aileron 5 provided with a slot 62 formed in an interior bracing structure 63 which is attached to the front hollow bracing tube 29. A pivot 64, carried on the upper 60 end of the support horn 6, passes through the slot 62 formed in the member 63.

Pivoted to the member 63 at 65 is a link 66 which is pivoted at 67 on the aileron horn 6. The link 66 passes through an aperture 68 in the lower 65 surface of the aileron 5.

It will be understood that in all of these forms of aileron shown, the linkages and constructions are duplicated adjacent the horns 6, and that is true of this construction as well.

70 In Figure 9 there is shown in dotted lines the movement of the aileron in its up and down positions. In the up position of the aileron the linkage causes the aileron to move bodily forward on the horn 6. In the down movement of the aileron 75 the aileron moves bodily backward on the horn

6. This linkage and construction moves the pivot point of the aileron on the horn so that when the center of pressure of the aileron is shifted by reason of its angular position, the moment of force of the pair to the pivots, i. e. the forces necessary to move the pair of ailerons, is such that for the various angular positions of the ailerons the unbroken line in Fig. 3 approximately represents graphically the action which takes place.

It is to be understood that the graph in Fig. 3 is not intended to represent accurately the action which occurs in the case of every aileron pair, but is merely indicative of what may be, within reasonable limits of error, expected of the ailerons shown in this application.

In Figure 10 I have shown the aileron 5 attached to a support 70 which is relatively long and slopes backward. The support 70 is pivoted at its lower rear end to a pivot 71 formed on a support horn 72 which has a relatively great 20 backward angular slope with respect to the upper surface of the wings 4. The aileron control rod 10 is pivoted at 73 to a front part of the support 70. With this arrangement the aileron is pivoted on the horn 72 at a point well below and 25 behind the normal center of pressure of the aileron. The different positions of the aileron with respect to its hinged point 71 is shown in dotted lines and the construction is such that the shift in center of pressure on the pair of 30 ailerons is compensated for by change in the moment arm from the center of pressure to the pivots, so that the stick forces necessary to operate the pair of ailerons are within the limits of tolerance represented by the unbroken line in 35 Fig. 3.

In Figs. 11 and 12 I have shown an aileron of warped construction. In Figs. 11 and 12 the trailing edge of the aileron is indicated by the line 75. The aileron is warped, as is clearly apparent from these two figures. A line 76 indicates the trailing edge of the wing 4. This warped construction is such that when the center of pressure on one portion of the area shifts in one direction, the center of pressure on the other 45 portion of the aileron shifts in the other direction, and the sum of the center of pressure on the two areas on each aileron in the pair tends to permit the stick forces for the pair to approximate the unbroken line shown in the graph, 50 Fig. 3.

I claim:

1. In an aircraft having a transverse wing extending on either side of the center line of the craft and roll control mechanism including a 55 control member, roll producing devices on either side of the craft and mounted on said wing, connections between said control member to said devices, and means whereby there is a substantially straight line increase in forces necessary to move 60 the control member as the roll producing devices are moved from their neutral positions.

2. An aircraft roll control mechanism comprising a control member, a roll producing device, operating connections between the control member 65 and the roll producing device, and means whereby there is a substantially straight line increase in forces necessary to move the control member as the roll producing device is moved from its neutral position.

3. In an aircraft having a transverse wing extending on either side of the center line of the craft and roll control mechanism including a control member, ailerons on either side of the craft and mounted on said wing, connections between 75

- said control member to said ailerons, and means whereby there is a substantially straight line increase in forces necessary to move the control member as the ailerons are moved from their neutral positions.
4. An aircraft roll control mechanism comprising a control member, an aileron having a fixed slot, operating connections between the control member and the aileron, and means whereby there is a substantially straight line increase in forces necessary to move the control member as the aileron is moved from its neutral position.
5. In an aircraft having a transverse wing extending on either side of the center line of the craft and roll control mechanism including a control member, interlinked single cambered ailerons having cambered upper surfaces on either side of the craft and mounted on said wing, connections between said control member to said ailerons, and means including fixed slots located at the forward edge of each aileron whereby there is a substantially straight line increase in forces necessary to move the control member as the ailerons are moved from their neutral position.
6. In an aircraft having a transverse wing extending on either side of the center line of the craft and roll control mechanism including a control member on either side of the craft and mounted on said wing and above the upper surface thereof, connections between said control member to said ailerons, and means whereby there is a substantially straight line increase in forces necessary to move the control member as the ailerons are moved from their neutral position.
7. Ailerons having warped surfaces so that upon movement of the pair to angular positions from the neutral the center of pressure with respect to designed areas on each aileron shifts so that the stick forces required to move the pair of ailerons to relatively large plus and minus angles from the neutral increase in substantially direct proportion to the angular movement.
8. A pair of warped ailerons whose center of pressure shifts are such in varying positions of up and down movement of the pair as to permit the stick forces to increase in substantially straight line fashion.
9. In a pair of ailerons, relatively long aileron supports, backwardly sloping horns, pivots on the horns on which the supports are pivoted, the supports being of such a length and so related to the ailerons and the horns that shift in center of pressure of the pair is compensated for by change in the moment arms to the pivots.
10. In a pair of ailerons, aileron supports, aileron horns, pivots on the horns on which the supports are pivoted, the supports being of such a length and so related to the ailerons and the horns that shift in center of pressure of the pair

is compensated for by change in the movement arms to the pivots.

11. An aileron having a slot therein, a pivot for the aileron mounted in the slot, a supporting horn for the aileron carrying the pivot, a link pivoted on the aileron at one end and on the supporting horn at the other whereby moving the aileron bodily with respect to the pivot is effected in moving from the neutral position.

12. An aileron having a slot therein, a pivot for the aileron mounted in the slot, linkage for shifting the axis of pivoting of the aileron about the pivot during pivoting.

13. In a pair of slotted ailerons, pivots for the ailerons mounted in the slots, means for so moving the aileron on the pivots while moving through up and down positions from the neutral as to compensate for shifts in center of pressure by varying the moment arms about the pivots.

14. A single cambered aileron comprising a flap on the lower rear surface of the aileron adapted to have its trailing edge in positions of extension and retraction lie substantially within the locus of perpendiculars to the datum lines of the airfoil sections of the aileron and passing through the trailing edge of the aileron, a horn on the flap, a spring within the aileron attached to the interior thereof at one end and at its other end to the horn on the flap, and a link pivoted to the horn at one end and slidably pivoted at its other end to a pivot fixed with respect to the aileron.

15. A single cambered aileron comprising a flap on the lower rear surface of the aileron adapted to have its trailing edge in positions of extension and retraction lie substantially within the locus of perpendiculars to the datum lines of the airfoil sections of the aileron and passing through the trailing edge of the aileron, linkages to cause downward movement of the flap with respect to the aileron on downward movement of the aileron.

16. A double cambered aileron comprising a flap pivoted on the upper rear surface of the aileron and having its trailing edge in its retracted position adjacent the trailing edge of the aileron, a horn on the flap, a spring within the aileron attached to the interior thereof at one end and at its other end to the horn on the flap, and a link pivoted to the horn at one end and slidably pivoted at its other end to a pivot fixed with respect to the aileron.

17. A single cambered aileron comprising a flap pivoted on the lower rear surface of the aileron and having its trailing edge in its retracted position adjacent the trailing edge of the aileron, a horn on the flap, a spring within the aileron attached to the interior thereof at one end and at its other end to the horn on the flap, and a link pivoted to the horn at one end and slidably pivoted at its other end to a pivot fixed with respect to the aileron.

EDWARD F. ZAPARKA
